Application January 12, 1933. Serial No. 651,264

5 Claims. (Cl. 190—41)

The present invention relates in general to improvements in the construction of luggage carriers of the type wherein a plurality of garments may be effectively packed and concealed.

5 Generally defined, an object of the invention is to provide an improved luggage carrier which is simple and compact in construction, and which is moreover highly efficient in operation.

It has heretofore been proposed, as shown and 10 described in copending application Serial No. 587,324, filed January 18, 1932, to provide a luggage carrier consisting of hingedly connected main and cover sections, wherein a plurality of independent garment carrier bars were mounted 15 in the cover section and cooperated with the garment folding rod of a pivoted frame to pack and to confine a number of garments within the cover section. In this prior device the garment carrier bars were supported in the cover section 20 independently of each other and were locked in place by movement of the garment supporting frame into loading position. Because of the fact that the garment carrier bars were independently supported in the cover section, it necessitated the 25 provision of independent retaining sockets for each bar, and it was also impossible to simultaneously remove all of the bars as a unit.

It is a more specific object of the present invention to provide an improved luggage carrier 30 which obviates the defects of this prior device and which provides garment supporting mechanism of simpler and more compact construction adapted to effectively confine a maximum number of garments within a minimum space.

35 Other more specific objects of the invention may be defined as follows:—

To provide an improved garment support for luggage carrier cases or the like, which may be readily applied to a carrier case and utilized to 40 store one or more garments therein in a compact manner and without undesirably wrinkling or damaging the garments.

To provide an improved wardrobe case of relatively light construction, wherein a plurality of 45 independent garments may be neatly stored and locked within the case, and in which the several garments may be conveniently and independently inserted or removed.

To provide a new and useful garment support- 50 ing mechanism embodying a plurality of carrier bars and a common supporting bracket for the bars forming a unit which may be stored within a container, or removed from storage and hung upon a fixed support when the container is not 55 en route.

To provide a relatively small container or hous- 60 ing having therein readily manipulable means for storing a number of full length garments, while maintaining considerable free space for the re- ception of other luggage.

To provide an improved luggage carrier case 65 comprising hingedly connected main and cover sections, wherein a plurality of garments may be supported upon carrier bars mounted in a sup- porting bracket which is in turn mounted directly in the cover section, and in which all of the gar- ments may be compactly folded over a swinging rod carried by a frame which is movable into and out of the cover section and which serves to lock the bar supporting bracket in place when the 70 mechanism is in loading position.

To provide an improved luggage transporting 75 container adapted to snugly confine and to lock a plurality of neatly folded garments into the cover thereof so that the garments cannot become disarranged or displaced during transportation of the container.

To provide an improved garment supporting 80 frame structure having a folding rod which is adapted to effectively fold and confine delicate garments without danger of creasing or of dam- aging the garments coacting therewith.

To provide a wardrobe case and garment sup- 85 porting means associated therewith, which are of light weight but rigid and durable in construc- tion, and which may be manufactured and sold at minimum cost.

To provide an improved garment supporting bracket having a plurality of garment carrier bars 90 detachably associated therewith in a manner to prevent the bars from accidentally becoming dislodged from the bracket.

To provide other improvements in the construc- 95 tion and mode of operation of garment support- ing mechanisms for wardrobe cases, whereby the efficiency of such mechanisms is enhanced to a maximum while the mode of manipulation is simplified as much as possible.

These and other objects and advantages will 100 be apparent from the following detailed descrip- tion.

Some of the novel features of luggage carrier construction disclosed but not specifically claimed herein form the subject of the copending appli- 105 cation hereinabove referred to, which discloses garment supporting mechanism comprising a plu- rality of garment carrier bars mounted in the cover section of the case and a garment folding frame cooperating with the bars to confine the 110

garments within the cover section and to simultaneously lock the bars in loaded position.

A clear conception of embodiments of the several features constituting the present invention 5 and of the mode of constructing and of utilizing luggage carriers built in accordance therewith, may be had by referring to the drawings accompanying and forming a part of this specification in which like reference characters designate the 10 same or similar parts in the various views:

Fig. 1 is a front view of an open luggage carrier case showing the garment supporting frame swung over the main section of the case, preparatory to loading of the garment supporting mechanism;

Fig. 2 is a transverse vertical section through the open luggage carrier case, likewise showing the garment supporting frame positioned preparatory to loading of the supporting mechanism;

Fig. 3 is a similar vertical section through the open case, showing the garment supporting frame partially adjusted for confinement of the coacting garments within the cover section;

Fig. 4 is another similar section through the open case, showing a number of garments finally stored and confined within the cover section;

Fig. 5 is an enlarged front view of the removable garment supporting bracket or rack, showing the garment supporting bars detachably associated therewith;

Fig. 6 is a further enlarged end view of the bracket showing the bars therein;

Fig. 7 is a similarly enlarged opposite end view 35 of the bracket and bars;

Fig. 8 is a fragmentary sectional view of the main and cover sections of the case, showing an end view of one of the pivoting and confining sockets for the supporting frame and bar supporting bracket, showing the frame in position for the reception of garments during loading;

Fig. 9 is a similar view of the assemblage shown in Fig. 8, showing the garment supporting mechanism in finally loaded position;

Fig. 10 is a fragmentary section through the cover of the case, showing a top view of the garment supporting mechanism with the frame in loading position and of modified construction;

Fig. 11 is a section through the folding rod of 50 the modified supporting frame of Fig. 10, the section being taken along the line 11—11 of Fig. 10; and

Fig. 12 is a vertical section through the pivot portion of the garment supporting mechanism, taken along the line 12—12 of Fig. 8.

Although the invention has been shown and described herein as being specifically applied to a relatively small and light luggage carrier, it should be apparent that the novel features are more generally applicable to any type of luggage carrier, and it is not the intent to limit the invention by such specific disclosure.

The improved luggage carrier illustrated in the drawings comprises in general a main section 15 having a cover section 16 pivotally attached thereto by means of a hinge 17, and garment supporting mechanism of improved construction mounted entirely within the cover section 16. The main section may be provided with the usual carrying handle 18 and the cover section 16 may be swung into engagement with the main section 15 and locked thereto by means of the usual latches 19. The cover section 16 is held in substantially upright position when the main section 15 is disposed horizontally and the cover

section 16 is swung open, by means of retainers 20 of ordinary construction.

The improved garment supporting mechanism comprises generally a garment supporting frame 21 swingably supported in sockets 22 fixedly mounted on the side walls of the cover section 16 near the main hinge 17 and having an integral transverse garment folding rod 23 remote from the sockets 22; and a plurality of similar garment carrier bars 24 detachably associated with a supporting bracket 25 which is in turn adapted to be detachably connected to the sockets 22.

The supporting frame 21 is shown in detail in Figs. 8 to 11 inclusive, and may be constructed of metal and of U-shaped form, and the pivoted ends of the sides of this frame are connected to the sockets 22 by means of pivots 26 and have lateral extensions 27 provided with slots 28 extending across the pivotal axis, these slots being spaced from the inner ends of the fixed pivots 26. The sockets 22 which are attached directly to the cover section 16, have integral wall portions 29 spaced from and extending parallel to the side walls of the cover section, and the lateral 100 extensions 27 of the frame ends are disposed in close proximity to these socket wall portions 29. The wall portions 29 have slots 30 which register with the slots 28 when the frame 21 is swung into the position shown in Fig. 8, and also have 105 circular openings 31 communicating with the slots 30 and at all times exposed to the inner portions of the slots 28. When the frame 21 is swung to the position indicated in Fig. 9, the slots 28, 30 are out of registry with each other 110 and this disposition of the mechanism will be termed locking position. The rod 23 may be formed as a tubular rod 23' having elliptical cross section as shown in Figs. 10 and 11, and when such tubular rod 23' is utilized, it is preferable to provide the frame 21 with extensions 21' at the ends of the rod 23'. This tubular type of rod 23' may be rigidly attached to the sides of the frame 21 in any suitable manner and may be polished to present a smooth and gradually curved 115 garment engaging edge.

The garment supporting bracket 25 is shown in detail in Figs. 5 to 7 inclusive, and consists of a pair of spaced side walls 32, 33 rigidly interconnected by cross members 34. The side wall 32 of the bracket 25 has therein an elongated opening 35 having closed opposite ends, and the other side wall 33 has therein a similar opening 36 having one end closed and the other open. The opening 36 has a widened portion 37 near the 120 open end thereof and the wall 33 has rounded projections 37' which form detents on the opposite sides of the main opening 36 as clearly shown in Fig. 7. The bracket side wall 33 also has an outwardly bent end portion 38 near the open end 125 of the opening 36, the bending of this end portion 38 automatically providing an open end for the opening 36. Each of the bracket side walls 32, 33 is also provided with an integral lug 39, and these lugs are adapted to be inserted into the slots 30 of the pivot sockets 22 and to be rotated within the circular openings 31 as will be clearly apparent from Figs. 8 and 9. The bracket 25 may moreover be provided with an adjustable hanger hook 40 which normally lies against the members 34, but which may be adjusted to the dot and dash line position of Fig. 5 for the purpose of hanging the bracket 25 from a clothes hook or the like. The garment carrier bars which may be formed of wood, have reduced metal ends 41

adapted to coat with the bracket openings 35, 36 as clearly shown in Figs. 5, 6 and 7.

The luggage carrier may also be provided with a final garment confining flap 42 made of cloth, 5 one end of which is permanently attached to the cover section 16 near the main hinge 17, and the opposite end of which is freely movable and has a catch 43 adjustably connected thereto. The catch 43 is cooperable with a hook 44 permanently attached to the swinging end of the cover section 16, in order to confine the loaded garments 45 within the cover section 16 as shown in Fig. 4. The main section 15 of the luggage carrier may also have stop blocks 46 secured to the 10 inner portions of the side walls thereof in order to limit the forward and downward swing of the frame 23 as indicated in Fig. 2.

When it is desired to load the improved luggage carrier case with garments 45, the individual garments may first be folded over the carrier bars 24 which may then be inserted in the elongated openings 35, 36 of the bracket 25 in the manner indicated in Fig. 5, either while this bracket 25 is hanging on the hook 40, or while 25 it is disposed as shown in Figs. 1 and 2. After the lugs 39 of the bracket 25 have been inserted within the slots 28, 30 and the garments 45 have been arranged as indicated in Fig. 2, the frame 21 may be swung upwardly away from the stop blocks 46 as in Fig. 3, whereupon the rod 23 becomes effective to fold the garments 45 midway between the bars 24 and the garment ends. This swinging of the frame 21 also causes the bracket 25 to swing and moves the retainer lugs 39 out 30 of alignment with the slots 30, thereby automatically locking the bracket 25 within the sockets 22. The frame 21 may obviously be swung entirely into the cover section 16 as in Figs. 4 and 9, whereupon the bracket end wall 33 coacts with 35 the cover section to positively confine the bar ends 41 within the openings 35, 36. With the frame 21 swung entirely into the cover section 16, the flap 42 may be extended over the free ends of the garments and fastened in place by 40 applying the adjustable catch 43 to the hook 44 and by pulling on the strap to which the catch 43 is adjustably attached, thus neatly and compactly loading the garments 45 within the cover section 16 and leaving the main section 15 free 45 for the storage of other luggage. The luggage carrier may thereafter be closed and transported without danger of having the garments 45 disarranged.

The removal of one or more of the garments 45 50 may be just as readily effected, by first removing the flap 42 and by subsequently returning the supporting mechanism and the garments 45 to the position shown in Fig. 1. When this is done, the bracket 25 is again automatically released 55 and may be lifted bodily together with the bars 24 and the garments 45 associated therewith, from within the sockets 22 and away from the frame 21. Or, if so desired, the bracket 25 may 60 be permitted to remain within the cover section 16, and the individual bars 24 removed therefrom. It is to be noted that the peculiar construction of the opening 36 with its widened portion 37 and the rounded projections 37', will 65 effectively prevent the bars 24 from accidentally dropping out of the openings 35, 36, but that the detents adjoining the projections 37' do not interfere with the free intentional removal of the bars 24. This action of the detents in preventing 70 accidental removal of the upper bar 24 is illus-

trated in Fig. 7, and is advantageous when the bracket 25 is removed from the sockets 22.

The improved construction of the frame 21 shown in Figs. 10 and 11, will prevent sharp creasing and possible cutting of the garments 45 by virtue of the formation of the rod 23', and the extensions 21' will serve to prevent the garments from slipping off of the ends of the rod. The elliptical cross-section of the rod 23' also stiffens the frame 21 thereby adding rigidity to 80 the structure.

From the foregoing description, it will be apparent that the invention provides simple, compact and readily manipulable means for permitting one or more full length garments to be effectively packed within a container of small size. The detachable mounting of the bracket 25 directly within the cover section 16 and the independent removability of the garment carrier bars 24, make the device flexible in use, and permit hanging of the garments when not en route. The frame 21 serves merely as a means for folding the garments during loading, and the flap 42 effectively finally confines the garments 45 and the loading mechanism, within the cover. When 100 finally loaded, all elements of the structure are effectively locked in place, and the improvement has proven extremely efficient in commercial use.

It should be understood that it is not desired to limit the invention to the exact details of construction herein shown and described, for various modifications within the scope of the claims may occur to persons skilled in the art.

It is claimed and desired to secure by Letters Patent:—

1. A luggage carrier comprising, hingedly connected main and cover sections, a frame pivotally mounted for swinging movement into and out of one of said sections, a bracket removably supported directly within said section, a plurality 115 of removable garment carrier bars carried by said bracket, means for locking said bracket in its support by pivotal movement of said frame into said section, and means operable by the swinging movement of said frame for confining said 120 garment bars on said bracket.

2. A luggage carrier comprising, hingedly connected main and cover sections, a frame having a garment folding rod movable along a fixed path into and out of said cover section, a bracket 125 removably supported within said cover section, a plurality of removable garment carrier bars carried by said bracket, means for locking said bracket in its support by movement of said frame into said cover section, and a flap for maintaining said frame and the garments coacting therewith within said cover section.

3. A luggage carrier comprising a main section and a cover section hingedly connected thereto, a garment folding frame having its inner ends 135 pivotally connected to one of said sections adjacent the hinged connection between the sections and having a transverse garment supporting member spaced from said inner ends, an elongated bracket, a plurality of elongated garment carrier bars cooperable with the garment supporting member of the folding frame to support garments within the case, means on said bracket for removably holding said bars, and means on opposite sides of the cover section for removably holding said bracket in a position substantially parallel to the hinged connection between the sections whereby said bracket may be bodily removed from the case with the plurality of bars independently of the folding frame.

4. A luggage carrier comprising a main section and a cover section hingedly connected thereto, a garment folding frame having its inner ends pivotally connected to one of said sections adjacent the hinged connection between the sections and having a transverse garment supporting member spaced from said inner ends, an elongated bracket, a plurality of elongated garment carrier bars cooperable with the garment supporting member of the folding frame to support garments within the case, means on said bracket for removably holding said bars, and means on opposite sides of the cover section for removably holding said bracket in a position substantially parallel to the hinged connection between the sections whereby said bracket may be bodily removed from the case with the plurality of bars independently of the folding frame, said bracket being rotatable on its holding means whereby when the frame with garments loaded thereon is moved on its pivotal connection it will maintain a fixed relationship between the bracket and the frame and eliminate friction on the garments. 80
5. A luggage carrier comprising a main section and a cover section hingedly connected thereto, a garment folding frame having its inner ends pivotally connected to one of said sections adjacent the hinged connection between the sections and having a transverse garment supporting member spaced from said inner ends, an elongated bracket, a plurality of elongated garment carrier bars cooperable with the garment supporting member of the folding frame to support garments within the case, means on said bracket for removably holding said bars, and means on opposite sides of the cover section for removably holding said bracket in a position substantially parallel to the hinged connection between the sections whereby said bracket may be bodily removed from the case with the plurality of bars independently of the folding frame, said bracket being rotatable on its holding means whereby when the frame with garments loaded thereon is moved on its pivotal connection it will simultaneously lock said plurality of bars on said bracket and maintain a fixed relationship between the bracket and the frame so that friction on the garments is eliminated. 85
